DESIGN FOR A DENTURE BRUSH

Paul B. Brandt, Augusta, Kans.

Application August 27, 1947, Serial No. 141,086

Term of patent 14 years

(Cl. D9—2)

To all whom it may concern:

Be it known that I, Paul B. Brandt, a citizen of the United States, residing at Augusta, in the county of Butler and State of Kansas, have invented a new, original, and ornamental Design for a Denture Brush, of which the following is a specification, reference being had to the accompanying drawings, forming part thereof.

Figure 1 is a view in top plan of a denture brush, embodying my new design;

Figure 2 is a view in side elevation; and

Figure 3 is a view in end elevation.

I claim:

The ornamental design for a denture brush, substantially as shown.

PAUL B. BRANDT.
